Standard Gas Equipment Corporation, Balti-
more, Md., a corporation of Maryland

Application September 26, 1946, Serial No. 133,599

Term of patent 14 years

(Cl. D81—25)

To all whom it may concern:

Be it known that I, Richard I. Felver, a citizen of the United States, residing at Pittsburgh, county of Allegheny, State of Pennsylvania, have invented a new, original, and ornamental Design for a Splash Panel Accessory Unit for Cooking Stoves, of which the following is a specification, reference being had to the accompanying drawing, forming part thereof.

Figure 1 is a top plan view of my new design for a splash panel accessory unit for cooking stoves.

Figure 2 is a front elevational view.

Figure 3 is a side elevational view.

Figure 4 is a cross sectional view taken on the line 4—4 of Figure 2.

I claim:

The ornamental design for a splash panel accessory unit for cooking stoves, as shown.

RICHARD I. FELVER.
